Primary Examiner — Ian Simmons*Assistant Examiner* — Shannon Morgan(74) *Attorney, Agent, or Firm* — Saidman DesignLaw Group, LLC(57) **CLAIM**

The ornamental design for a display screen or portion thereof with graphical user interface, as shown and described.

DESCRIPTION

The FIGURE is a front view of a display screen or portion thereof with graphical user interface showing our new design. The dot-dash broken line represents a display screen; the dot-dash broken line forms no part of the claimed designs. The dashed line outside of the dot-dash broken line represents structure which forms no part of the claimed design. The dashed lines within the dot-dash broken line represent portions of the graphical user interface which form no part of the claimed design.
